FLYWHEEL MAGNETO
Russell E. Phelon, West Springfield, Mass.

Filed June 13, 1946, Serial No. 676,413
14 Claims. (Cl. 171—209)
The invention relates to a high tension magneto of the flywheel type, and, particularly, to such a magneto adapted for use with an internal combustion engine. A magneto embodying the invention has a stationary core structure and a rotatable field structure which surrounds the core structure.

A magneto of the type here involved has heretofore ordinarily included a rotatable member or flywheel of nonmagnetic material, carrying one or more circumferentially charged permanent magnets and the pole pieces therefor. The formation of the flywheel from nonmagnetic material has been deemed necessary in order that the magnetic circuits of the magnets might be independent of the said flywheel, thus avoiding leakage of magnetic flux through the said flywheel to other parts of the magneto. This has resulted in high cost, as a nonmagnetic material, such as brass, is much more expensive than a magnetic material, such as steel.

In accordance with the present invention either the entire flywheel or a substantial portion thereof is formed of magnetic material and the said flywheel, or at least the magnetic portion thereof, cooperates with the magnet or magnets to constitute a magnetic circuit. The flywheel, or at least the magnetic portion thereof, is preferably magnetically insulated from the core structure in order to reduce to a minimum the flow of magnetic flux from one to the other.

The general object of the invention is to provide a magneto of the type set forth having the flywheel formed in whole or in substantial part of magnetic material. In accordance with the said general object the flywheel carries one or more radially charged permanent magnets engaging therewith at their outer extremities, and means such as pole pieces are provided in association with the magnet or magnets which provide two circularly spaced pole faces movable in close proximity to the outer faces of the poles of the core structure.

A more specific object of the invention is to provide various advantageous features involving the relationship of the magnets and pole pieces to each other and to the poles of the core structure.

Other objects of the invention will be apparent from the drawing and from the following specification and claims.

In the drawing I have shown in detail a preferred embodiment of the invention, but it will be understood that various changes may be made from the construction shown, and that the drawing is not to be construed as defining or limiting the scope of the invention, the claims forming a part of this specification being relied upon for that purpose.

Of the drawing,

Fig. 1 is a vertical sectional view taken along the line 1—1 of Fig. 3.

Fig. 2 is a view similar to Fig. 1 but showing the rotatable field structure in a different position.

Fig. 3 is a longitudinal vertical sectional view taken along the line 3—3 of Fig. 2.

Fig. 4 is a diagram of electrical connections.

The core structure of the magneto is nonrotatable and as shown in the drawing, it is carried by a frame 10 having a bushing 12 which provides a bearing for a rotatable shaft 14. The shaft 14 may be an extension of the crankshaft of the engine with which the magneto is to be used, and in any event it is rotated in timed relationship with the engine. The core structure comprises a magnetic core 16 preferably laminated and arranged to provide a plurality of circularly spaced poles having arcuate faces which are concentric with the axis of the shaft 14 and equidistant therefrom. The poles of the core structure are all within an arc of approximately 180° or less and are ordinarily at one side of a diametral plane through the axis of the shaft. Primary and secondary generating coils surround one of the poles.

As shown the core structure has three poles 18, 20 and 22, and primary and secondary coils 24 and 26 surround the intermediate pole 20. The primary coil has a relatively small number of turns, as for instance 175, and the secondary coil has a relatively large number of turns, as for instance 10,000.

The primary coil 24 is suitably grounded, for instance by being connected to one of the screws 28, 28 which hold the core 16 in place on the frame 10. The ungrounded end of the primary coil is connected by means of an insulated conductor 30 with breaker points 32 and 34. The point 34 is grounded and the point 32 is carried by a rocker arm 36 pivoted at 38 to the frame 10. The rocker arm 36 has an extension 40 which is engaged by a cam 42 mounted on the shaft 14. A spring 44 serves to bias the arm 36 to move the point 32 into engagement with the point 34, and this spring, or an auxiliary conductor associated therewith, serves to provide an electrical connection between the conductor 30 and the said point 32. When the shaft 14 is rotated the cam 42 oscillates the rocker arm 36 to make and break the electrical connection between the points 32 and 34. A condenser 46 is connected in parallel with the breaker points 32 and 34 in accordance with customary practice.

The secondary coil 26 is suitably grounded, for instance by being connected with the same screw 28 which is used for grounding the primary coil. The secondary coil is provided at its ungrounded end with an insulated conductor 48 which extends to the spark plug 50 of the engine.

The rotatable field structure of the magneto

includes a flywheel which is carried by the shaft 14 so as to be rotatable therewith. The flywheel is provided with a connecting member 52 which is formed of magnetic material, this connecting member preferably being an annular flange which surrounds the core structure, more particularly the core 16 and the coils 24 and 26 thereof. The flange 52 is carried by and preferably formed integrally with a disc-like portion 54 which is connected with the shaft 14. The flange or member 52 and the disc-like portion 54 of the rotatable unit may be formed as a unit from a single piece of magnetic material, such as steel, by a simple stamping or drawing operation. However, if preferred, a casting may be substituted.

The connecting member or flange 52 is preferably magnetically insulated from the core structure, particularly the poles thereof. As shown, such magnetic insulation is attained by providing a hub 56 of nonmagnetic material, such as brass. The hub 56 is soldered or brazed or otherwise connected with the disc-like portion 54 and is adapted to be directly engaged with the shaft 14. As shown, the end portion of the shaft 14 is tapered to fit a correspondingly tapered opening in the hub 56 and a key is provided which fits suitable keyways to insure rotation of the hub in unison with the shaft. The hub 56 is held in place by a nut 58 engaging a threaded portion of the shaft.

Carried by the connecting member or flange 52 is at least one radially extending member and ordinarily there are two such members 60 and 62. At least one of the members is a radially charged magnet and ordinarily both of the members are magnets. The magnets are formed from a special alloy having a high coercive force. The outer extremities of the members or magnets directly engage the internal face of the flange 52 and the said members or magnets are circularly spaced and are at one side of a diametral plane through the axis of rotation. The said members or magnets are within an arc of the flange 52 which is less than 180° and ordinarily less than 120°, being thus enabled to cooperate with the relatively closely spaced poles of the core 16. The spacing is such that the two members or magnets can register simultaneously with the intermediate pole of the core structure and with one of the other poles thereof.

As stated at least one of the members 60 and 62 is a magnet, and means are provided which are connected with the inner extremity of the magnet and with the connecting member or flange 52 for providing two circularly spaced pole faces of opposite polarity which are movable in close proximity to the outer faces of the poles of the core structure and which are at one side of a diametral plane through the axis of rotation. As shown, both of the members 60 and 62 are magnets which are oppositely charged and which therefore have opposite polarity. The said means for providing pole faces of opposite polarity are pole pieces 64 and 66 carried respectively by the magnets at the inner extremities thereof. The inner faces of the pole pieces are concentric with the axis of the shaft and are so spaced therefrom as to be adapted to move in close proximity to the pole faces 18, 20 and 22 of the core 16. It will be seen that a magnetic circuit is established through the said magnets and their pole pieces and also through that portion of the flange 52 which intervenes between the two magnets.

The members or magnets 60 and 62 and their pole pieces 64 and 66 may be connected with the

flange 52 by mechanical connecting means, such as rivets, but I prefer to connect them by brazing or soldering. The magnets are brazed or soldered to the flange 52 and the pole pieces are brazed or soldered to the magnets. The magnets have a critical temperature above which they cannot be heated without damage, but by using a suitable solder, such as a silver-copper alloy, and by closely controlling the temperature, soldering 10 can be effected without damage.

A counterweight 68 is provided, this being shown as secured to the internal face of the flange or member 52 opposite the magnets by soldering or otherwise. In practice the counterweight is initially slightly heavier than the magnets and the pole pieces, and then one or more holes 70 are drilled therein in order to obtain an exact balance.

When the field structure rotates in the clockwise direction the leading pole piece 66, marked S in Fig. 1, registers with the center pole 20 of the core 16 and at the same instant the trailing pole piece 64, marked N in Fig. 1, registers with the left pole 18 of the core 16, thus establishing a magnetic circuit through the center pole in one direction. As the field structure continues to rotate the leading pole marked S leaves the center pole 20 and comes into register with the right pole 22 of the core 16. At the same instant 30 the trailing pole N leaves the left pole 18 and comes into register with the center pole 20, as shown in Fig. 2. At this instant the direction of the magnetic circuit through the center pole 20 is suddenly reversed and a maximum value of voltage 35 is generated in the primary coil 24. The cam 42 is so positioned as to separate the breaker points 32 and 34 at the instant of maximum voltage in the primary coil, thus generating a high voltage in the secondary coil 26 which is connected with the spark plug 50. In a high tension magneto it is generally desirable to maintain a relatively high remanence of flux in the magnets. In a design such as the one described this is particularly desirable because of the short length in the radial direction of the magnets relative to the area in cross section at right angles to the radial direction. This high remanence is maintained by providing adequate leakage of the flux during the 40 portion of the rotation of the rotor when the pole pieces are not in register with the core faces. Flux leakage is in proportion to the area of the air gap between oppositely charged surfaces. For this reason the pole pieces 64 and 66 project either 45 axially or circularly, and preferably both axially and circularly, beyond their magnets, thus providing a larger area of air gap between one pole piece and the other oppositely charged one, and between each pole piece and the oppositely charged annular flange 52. Magnetic leakage is also indirectly proportional to the length of the air gap. For this reason the oppositely charged pole pieces are extended towards each other to approach each other as closely as possible without interfering with the effective register of the pole pieces with the faces of the poles of the stationary core.

The circular and axial projection of the pole pieces beyond their magnets is also highly important for facilitating manufacture. As has been stated, the pole pieces are brazed or soldered to the magnets and the projection of the pole pieces beyond the magnets provides exposed faces to which the brazing or soldering material can 55 adhere.

The magnets 60 and 62 are circularly spaced

from each other to an extent greater than the width of the intermediate pole 20 of the core structure, and the pole pieces 64 and 66 project toward each other to such an extent that the width of the gap between them is less than the width of the said intermediate pole 20. Thus the spacing of the magnets is such that they cannot register simultaneously with the said intermediate pole, but the pole pieces on the magnets can register simultaneously with the said pole so as to provide a sudden reversal in the magnetic circuit through the said pole. Preferably the two magnets are of substantially the same size, but the leading pole piece 66 projects beyond the leading magnet 62 to relatively large extents and the trailing pole piece 64 projects beyond the trailing magnet 60 to smaller extents. The said leading magnet 62 has a circular width which is less than the spacing between the intermediate core pole 20 and the forward core pole 16. The extents of circular projection of the pole piece 66 are such that the said pole piece can simultaneously register with both of the said core poles.

In previous designs of a flywheel magneto having a similar core structure, a single magnet was provided which was charged in the circular direction to provide two magnetic poles of opposite polarity. Such a magnet could not be placed in close proximity to any part of a flywheel made of magnetic material because the magnetism would leak from one end of the magnet to the other through the magnetic portion of the flywheel in preference to causing flux to pass through the coil core of the core structure. The present invention eliminates this difficulty since the magnet or magnets are charged radially and the entire flywheel, or at least the magnetic portion thereof, attains a magnetic charge which is intermediate between the two poles. It is advisable, however, to insulate magnetically between the magnetic portion or flange of the flywheel and the core structure since otherwise some of the magnetism could pass from the said portion or flange to the core structure without passing through the intermediate pole of the core structure which is surrounded by the generating coils. Since a magneto embodying the invention is primarily intended for use with an internal combustion engine which usually has a crankshaft of magnetic material, it is preferable to provide magnetic spacing at some point between the flywheel, or the magnetic portion thereof, and the core structure. In the construction shown in the drawing this insulation is provided, as already described, by the use of a hub 56 of nonmagnetic material which connects the flywheel with the shaft.

In the drawing I have shown a single pair of magnets, and I have shown a cam which separates the breaker points once during each revolution. It will be understood, however, that without departing from my invention two or more pairs of magnets may be provided circularly spaced from each other, and that the cam may be modified to separate the breaker points two or more times during each revolution.

What I claim is:

1. A flywheel magneto for an internal combustion engine comprising in combination, a rotatable shaft, a stationary core structure adjacent the shaft including three circularly spaced poles all positioned within an arc of approximately 180° or less and having their outer faces equidistant from the shaft axis and also including primary and secondary coils surrounding the intermediate

pole, a flywheel secured to the shaft and having an annular flange formed of magnetic material and surrounding the core structure, two permanent magnets directly engaging at their outer extremities with the internal face of the annular flange, the said magnets being circularly spaced within an arc of substantially less than 180° for simultaneous radial register respectively with the center pole of the core and with one of the other poles thereof and the said magnets being oppositely charged radially, and two separate circularly spaced pole pieces directly engaging the inner extremities of the respective magnets and having arcuate inner faces concentric with the axis of the shaft and movable in close proximity to the outer faces of the poles of the core structure which pole pieces cooperate with the magnets and with the annular flange of the flywheel to provide a magnetic circuit having inner pole faces of opposite polarity.

2. A flywheel magneto for an internal combustion engine comprising in combination, a stationary core structure including primary and secondary coils and a plurality of circularly spaced poles having their outer faces equidistant from an axis which poles are at one side of a diametral plane through the said axis, a rotatable flywheel adapted to be secured to an engine shaft rotatable about the said axis which flywheel includes an annular flange formed of magnetic material and at least partly surrounding the core structure, means for magnetically insulating the said annular flange of the flywheel from the core structure, two circularly spaced permanent magnets directly engaging at their outer extremities with the internal face of the annular flange, the said magnets being at one side of a diametral plane through the axis of rotation and being oppositely charged radially, and two separate circularly spaced pole pieces carried by the inner extremities of the respective magnets and having arcuate inner faces concentric with the axis of rotation and movable in close proximity to the outer faces of the poles of the core structure which pole pieces cooperate with the magnets and with the annular flange of the flywheel to provide a magnetic circuit having inner pole faces of opposite polarity.

3. A flywheel magneto for an internal combustion engine comprising in combination, a stationary core structure including primary and secondary coils and a plurality of circularly spaced poles having their outer faces equidistant from an axis which poles are at one side of a diametral plane through the said axis, a rotatable flywheel adapted to be secured to an engine shaft rotatable about the said axis which flywheel includes a circularly extending connecting member formed of magnetic material, the said connecting member being disposed radially outward from the core structure and having an internal face, means for magnetically insulating the said connecting member from the core structure, a radially charged permanent magnet directly engaging at its outer extremity with the internal face of the connecting member, and means connected with the inner extremity of the magnet and with the connecting member and providing two circularly spaced pole faces of opposite polarity which faces are movable in close proximity to the outer faces of the poles of the core structure and are at one side of a diametral plane through the axis of rotation.

4. The combination in a flywheel magneto for an internal combustion engine, of a stationary core structure including primary and secondary

coils and a plurality of circularly spaced poles having their outer faces equidistant from an axis which poles are at one side of a diametral plane through the said axis, a rotatable flywheel formed of magnetic material and including a disc-like portion adapted to be secured to an engine shaft rotatable about the said axis which flywheel also includes an integral annular flange surrounding the core structure, means for magnetically insulating the said flywheel from the core structure, two circularly spaced permanent magnets directly engaging at their outer extremities with the internal face of the annular flange, the said magnets being at one side of a diametral plane through the axis of rotation and being oppositely charged radially, and two separate circularly spaced pole pieces directly engaging the inner extremities of the respective magnets and having arcuate inner faces concentric with the axis of rotation and movable in close proximity to the outer faces of the poles of the core structure which pole pieces cooperate with the magnets and with the annular flange of the flywheel to provide a magnetic circuit having inner pole faces of opposite polarity, the said pole pieces projecting substantially beyond their respective magnets circularly and in both directions so as to provide magnetic leakage at the ends of the said pole pieces.

5. The combination in a flywheel magneto for an internal combustion engine, of a stationary core structure including primary and secondary coils and a plurality of circularly spaced poles having their outer faces equidistant from an axis which poles are at one side of a diametral plane through the said axis, a rotatable flywheel adapted to be secured to an engine shaft rotatable about the said axis which flywheel includes an annular flange formed of magnetic material and surrounding the core structure, two circularly spaced permanent magnets directly engaging at their outer extremities with the internal face of the annular flange, the said magnets being at one side of a diametral plane through the axis of rotation and being oppositely charged radially, and two separate circularly spaced pole pieces directly engaging the inner extremities of the respective magnets and having arcuate inner faces concentric with the axis of rotation and movable in close proximity to the outer faces of the poles of the core structure which pole pieces cooperate with the magnets and with the annular flange of the flywheel to provide a magnetic circuit having inner pole faces of opposite polarity, the said pole pieces projecting substantially beyond their respective magnets circularly and in both directions and the pole piece on the leading magnet projecting circularly to substantially greater extents than does the pole piece on the trailing magnet.

6. The combination in a flywheel magneto for an internal combustion engine, of a rotatable shaft, a stationary core structure adjacent the shaft including three circularly spaced poles having outer faces equidistant from the axis of the shaft which poles are at one side of a diametral plane through the said axis, the said core structure also including primary and secondary generating coils surrounding the intermediate pole, a flywheel secured to the shaft and having an annular flange of magnetic material surrounding the core structure, two circularly spaced permanent magnets directly engaging at their outer extremities with the internal face of the annular flange, the said magnets being at one side of a

diametral plane through the axis of rotation and being oppositely charged radially and the circular width of the leading magnet being less than the spacing between the intermediate core pole and the forward core pole, and two separate circularly spaced pole pieces directly engaging the inner extremities of the respective magnets and having arcuate inner faces concentric with the axis of the shaft and movable in close proximity to the outer faces of the poles of the core which pole pieces cooperate with the magnets and with the annular flange of the flywheel to provide a magnetic circuit having inner pole faces of opposite polarity, the said pole pieces projecting substantially beyond their respective magnets circularly and in both directions so as to provide magnetic leakage at the ends of the said pole pieces and the pole piece on the leading magnet projecting circularly to such extents that it can register simultaneously with the said intermediate and forward poles of the core structure.

7. In a flywheel magneto for an internal combustion engine, the combination of a stationary core structure including three circularly spaced poles having outer faces equidistant from an axis which poles are at one side of a diametral plane through the said axis, the said core structure also including primary and secondary coils surrounding the intermediate pole, a flywheel rotatable about the said axis and having an annular flange formed of magnetic material and at least partly surrounding the core structure, two circularly spaced members of magnetic material directly engaging at their outer extremities with the internal face of the annular flange, the said members being at one side of a diametral plane through the axis of rotation and at least one of them being a radially charged permanent magnet, and two separate pole pieces directly engaging the inner extremities of the respective radially extending members and having arcuate inner faces concentric with the axis of rotation and movable in close proximity to the outer faces of the poles of the core structure which pole pieces cooperate with the radially extending members and with the annular flange of the flywheel to provide a magnetic circuit having inner pole faces of opposite polarity, the said pole pieces projecting substantially beyond their respective magnets circularly and toward each other to provide magnetic leakage between them and the said pole pieces projecting to such extents that the circular width of the gap between them is less than the circular width of the intermediate pole of the core structure.

8. In a flywheel magneto for an internal combustion engine, the combination of a stationary core structure including a plurality of circularly spaced poles having outer faces equidistant from an axis and including primary and secondary generating coils surrounding one of the poles, a flywheel rotatable about the said axis and having an annular flange formed of magnetic material and surrounding the core structure, two circularly spaced permanent magnets directly engaging at their outer extremities with the internal face of the annular flange, the said magnets being oppositely charged radially, and two separate circularly spaced pole pieces directly engaging the inner extremities of the respective magnets and having arcuate inner faces concentric with the axis of rotation and movable in close proximity to the outer faces of the poles of the core structure, the said pole pieces cooperating with the magnets and with the annular flange of the fly-

wheel to provide a magnetic circuit having inner pole faces of opposite polarity and the said pole pieces projecting substantially beyond their respective magnets axially in both directions.

9. In a flywheel magneto for an internal combustion engine, the combination of a stationary core structure including a plurality of circularly spaced poles having outer faces equidistant from an axis and including primary and secondary generating coils surrounding one of the poles, a flywheel rotatable about the said axis and having an annular flange formed of magnetic material and surrounding the core structure, two circularly spaced permanent magnets directly engaging at their outer extremities with the internal face of the annular flange, the said magnets being oppositely charged radially, and two separate circularly spaced pole pieces directly engaging the inner extremities of the respective magnets and having arcuate inner faces concentric with the axis of rotation and movable in close proximity to the outer faces of the poles of the core structure which pole pieces cooperate with the magnets and with the annular flange of the flywheel to provide a magnetic circuit having inner pole faces of opposite polarity, the said pole pieces projecting substantially beyond their respective magnets axially in both directions and also projecting substantially beyond the respective magnets circularly in both directions.

10. In a flywheel magneto for an internal combustion engine, the combination of a rotatable shaft, a stationary core structure including three circularly spaced poles having outer faces equidistant from the axis of the shaft which poles are at one side of a diametral plane through the axis of the shaft, the said core structure also including primary and secondary generating coils surrounding the intermediate pole, a flywheel formed of magnetic material and including a disc-like portion secured to the shaft and also including an integral annular flange surrounding the core structure, means for magnetically insulating the annular flange of the flywheel from the core structure, two permanent magnets directly engaging at their outer extremities with the internal face of the annular flange which magnets are oppositely charged radially, the said magnets being at one side of a diametral plane through the axis of rotation and being circularly spaced from each other to an extent substantially greater than the width of the intermediate pole of the core structure, and two separate circularly spaced pole pieces directly engaging the inner extremities of the respective magnets and having arcuate inner faces concentric with the axis of the shaft and movable in close proximity to the outer pole faces of the core structure which pole pieces cooperate with the magnets and with the annular flange of the flywheel to provide a magnetic circuit having inner pole faces of opposite polarity, the said pole pieces projecting substantially beyond their respective magnets axially and in both directions and the said pole pieces also projecting substantially beyond their respective magnets circularly and in both directions and projecting toward each other to such extents that the circular width of the gap between them is less than the circular width of the intermediate pole of the core structure.

11. A rotor for a flywheel magneto comprising in combination, a rotatable flywheel adapted to be secured to an engine shaft and including an annular flange formed of magnetic material and having an internal face, two circularly spaced

permanent magnets directly engaging at their outer extremities with the internal face of the annular flange, the said magnets being at one side of a diametral plane through the axis of rotation and being oppositely charged radially, and two separate circularly spaced pole pieces carried by the inner extremities of the respective magnets and having arcuate inner faces concentric with the axis of rotation which pole pieces cooperate with the magnets and with the annular flange to provide a magnetic circuit having inner pole faces of opposite polarity.

12. A rotor for a flywheel magneto including in combination, a rotatable flywheel adapted to be secured to an engine shaft and including a circularly extending connecting member formed of magnetic material and having an internal face, a radially charged permanent magnet directly engaging at its outer extremity with the internal face of the connecting member, and means connected with the inner extremity of the permanent magnet and with the magnetic connecting member and providing two circularly spaced pole faces of opposite polarity which faces are at one side of a diametral plane through the axis of rotation.

13. A rotor for a flywheel magneto comprising in combination, a flywheel formed of magnetic material and including a disc-like portion adapted to be secured to an engine shaft and also including an integral annular flange, two circularly spaced permanent magnets directly engaging at their outer extremities with the internal face of the annular flange, the said magnets being at one side of a diametral plane through the axis of rotation and being oppositely charged radially, and two separate circularly spaced pole pieces directly engaging the inner extremities of the respective magnets and having arcuate inner faces concentric with the axis of rotation which pole pieces cooperate with the magnets and with the annular flange to provide a magnetic circuit having inner pole faces of opposite polarity.

14. A rotor for a flywheel magneto comprising in combination, a rotatable flywheel adapted to be secured to an engine shaft and including an annular flange formed of magnetic material and having an internal face, two circularly spaced permanent magnets directly engaging at their outer extremities with the internal face of the annular flange, the said magnets being at one side of a diametral plane through the axis of rotation and being oppositely charged radially, and two separate circularly spaced pole pieces directly engaging the inner extremities of the respective magnets and having arcuate inner faces concentric with the axis of rotation which pole pieces cooperate with the magnets and with the annular flange to provide a magnetic circuit having inner pole faces of opposite polarity, the said pole pieces projecting substantially beyond their respective magnets axially in both directions and also projecting substantially beyond their respective magnets circularly in both directions.
